CLAIM

The ornamental design for a jewelry setting, as shown and described.

DESCRIPTION

FIG. 1 is a front elevational view of a jewelry setting showing my new design for a necklace;

FIG. 2 is a perspective view of the jewelry setting of FIG. 1;

FIG. 3 is a top plan view of the jewelry setting of FIG. 1; and,

FIG. 4 is a left side elevational view of the jewelry setting of FIG. 1, the right side being a mirror image thereof.

The portions of the jewelry setting that are not shown in the drawings do not form any part of the claimed design. In addition, the broken lines in the figures are for illustrative purposes only and form no part of the claimed design.
